DESIGN FOR A COMB

Siegfried Behr, Flushing, N. Y.

Application November 3, 1943, Serial No. 111,580

Term of patent 14 years

(Cl. D86—8)

To all whom it may concern:

Be it known that I, Siegfried Behr, a citizen of the United States of America, residing in Flushing, county of Queens and State of New York, have invented a new, original, and ornamental Design for a Comb, of which the following is a specification, reference being had to the accompanying drawing, forming part thereof.

Fig. 1 is a front view of a comb showing my new design.

Fig. 2 is a top plan view thereof.

I claim:

The ornamental design for a comb, substantially as shown.

SIEGFRIED BEHR.
